UNITED STATES PATENT OFFICE.

JAMES W. EASTON, OF NEW YORK, N. Y.

COMMUTATOR-CONNECTION FOR DYNAMO-ELECTRIC MACHINES.

SPECIFICATION forming part of Letters Patent No. 373,971, dated November 29, 1887.

Application filed April 13, 1886. Renewed May 3, 1887. Serial No. 236,869. (No model.)

To all whom it may concern:

Be it known that I, JAMES W. EASTON, a subject of the Queen of Great Britain, residing in New York, in the county and State of New York, have invented certain new and useful Improvements in Devices for Connecting Armature-Coils with Commutator-Plates of Electric Machines, of which the following is a specification.

10 The invention relates to the means employed for connecting the terminals of the bobbins of armature-coils with the collector or commutator brushes of an electric machine—such, for instance, as a dynamo-electric generator.

15 The object of the invention is to provide means for conveniently attaching or connecting the parts, so that the jar occasioned by the motion of the armature and the relative movements of the parts shall not, by constantly bending the connection, cause it to break, and thus cause injury to the machine and a cessation of the current.

20 The invention consists in providing a yielding or flexible coupling which extends between each end of each bobbin and the corresponding commutator-plate, and which may be placed in position to connect the parts after the bobbins and plates are mounted. This flexible connection preferably consists of a 25 coil-spring which by being compressed may be slipped over a projection upon the commutator-plate and the corresponding end of the wire of the armature-bobbin.

25 In the accompanying drawings, Figure 1 illustrates one method of applying the flexible connection, and Fig. 2 a modification of the same.

30 Referring to the figures, A represents an armature-bobbin or section of the same, together with one terminal of its wires, as shown at B. A commutator-plate is represented at C, and this has formed upon it a lug or projection, c, extending toward the armature-bobbin. A coil-spring of any suitable resilient conducting material, D, is employed for connecting the two parts. By compressing this spring it is 35 readily slipped over the projection c and the end B of the armature-coil. The spring is made of such length that it will be retained under more or less tension when thus in position between the parts, and this will insure a

reliable electric connection. If desired, the respective ends of the spring may be soldered to the end of the armature-coil and the projection c, while the intervening portion will afford sufficient elasticity to prevent the jar of the machine and the relative movements of the parts from doing injury and from breaking the connection between the coupling and the connected parts; but usually it is unnecessary to solder the parts, for the pressure of the spring is found to be sufficient to maintain good electrical connections.

40 In some instances it is desirable to employ fusible connections between the bobbin-joints and the commutator-plates, so that the connections will be interrupted should the currents produced be such as to endanger the bobbins by overheating them. In an application of even date herewith, Serial No. 198,685, 45 there is described and claimed a fusible connection for such purpose.

45 By making the fusible wire or strip in the form of a coil-spring, as above described, a flexible fusible coupling or connection is formed and certain advantages of both are secured.

50 In the drawings, b represents the wire leading from the next preceding bobbin, which is fastened to the end of the bobbin B by being wound around it and soldered in a manner well understood, the end b' projecting therefrom and receiving the spring D.

55 In Fig. 2 the end of the spring D is represented as entering a small aperture, c', in the plate C, instead of extending over a projection upon the same. This construction may be found more desirable in some instances than the one shown in Fig. 1.

60 It is evident that for the purpose of repairing the machine the spring may be readily removed and replaced.

65 I claim as my invention—

1. The combination, with an armature-bobbin of an electric machine and a commutator or collector plate, of a compressible yielding connection between the two parts, substantially as described.

2. The combination, with an armature-coil of an electric machine and a collector-plate, of a coil-spring connecting the two electrically.

3. The combination, with an armature and a commutator or collector plate, of a coil-spring

surrounding the end of the wire of the armature and pressing against the commutator-plate, substantially as described.

4. The combination, with the conductor of an armature-bobbin, of a commutator or collector plate, a projection upon the same, and a coil-spring surrounding said projection and said conductor and pressed between them, substantially as described.

10 5. The combination, with the conductor of an armature-bobbin, a commutator or collector plate, a projection upon the same, and a coil-spring surrounding said projection and said conductor and soldered thereto.

6. The combination, with the armature-bob- 15 bins of an electric machine and the commutator or collector plates, of a fusible compressible connection between the same, substantially as described.

In testimony whereof I have hereunto sub- 20 scribed my name this 17th day of March, A. D. 1886.

JAMES W. EASTON.
